PERFORATING DEVICE FOR MESSAGE
TRANSMISSION

Waldo G. Rice, Chicago, Ill.

Application February 11, 1935, Serial No. 5,917

19 Claims. (Cl. 178—92)

This invention relates to reception and transmission devices and more particularly to electrical relay operated reperforators for enabling multiple telegraphic reception and transmission over multiplex circuits, although certain features thereof may be employed with equal advantage for other purposes.

It contemplates more especially the provision of electrically responsive reperforators or other signal recorders that are entirely solenoid actuated for connection to a telegraphic circuit through a transmission bank having a low energy drain so that their multiple connection will not impair primary signal transmission or reception.

Methods and devices now used to accomplish multiple reception and transmission involve or require rather extensive revision of the distributor and/or printer connections as well as modifications of resistance values. This renders the installation expense of multiple transmitters and/or retransmitters prohibitive in that extensive modifications in resistance values and wiring of the original or primary printer and/or distributor circuits are ordinarily necessary or required. Except for isolated and special instances, multiple reception and/or distribution has not been practiced although there is a great and important need therefor. Then, too, reperforators of known construction are intricate, involve a large installation cost for multiple simultaneous use, and generally comprise an expensive unit. Relaying of messages by manual reperforations for use with a transmitter at the receiving stations, is the substitute practice for electrically responsive multiple reperforation and distribution. Known methods and apparatus are expensive, involve much time, and entail additional labor which are factors that render multiple reception and distribution an important advance in electrical re-transmission and reception devices where such can be accomplished with equipment of the desired simplicity and flexibility and without entailing much time, expense or labor for installation in already existent circuits.

For instance, the present invention provides for simple, compact and inexpensive electrically operated reperforator units that can be connected between a distributor and printer in a multiplex setup by mere attachment of suitable plug and socket complements to the cut ends of the six wire channel preferably through a transmission bank of low energy drain. The reperforator unit has similar leads terminating in a

corresponding plug or socket complement so as to afford ready and instantaneous connection between the printer and distributor. Similarly the reperforator unit may be readily detached, and the printer circuits restored to their original circuit setup by simply coupling together of the plug and socket previously attached to the severed wires of the multiple channel.

It should be understood that in multiplex setups that utilize a cord and plug connection between the distributor unit and the printer plug, the intermediate relay unit and proposed reperforator are readily attachable by means of a cord terminating in an adapter plug. The adapter plug is a complement of the regular cord and plug provided between the distributor receptacle and the printer plug, thereby offering instantaneous attachment and detachment of the relay unit as well as the reperforator in such circuits. Reference has been made to multiplex circuits, but the relay unit comprising the subject matter of applicant's Letters Patent 2,023,290, and the reperforator embodying the teachings of the present invention, are likewise readily adaptable to simplex and duplex circuits operated on the start-stop method and employing printers provided with an independent selector magnet for each selector circuit as commonly used on multiplex channels, thereby offering wide usefulness and general flexibility on various types of circuits for multiplex reception and retransmission.

While an important feature of the relay unit or transmission bank is in the provision of relay coils of nominal or exceedingly low resistance values as compared with the comparatively high resistances of the regular printer coils and other resistances comprising the total resistance of each printer circuit usually though not necessarily employing six coils in number, yet an important feature of the reperforator is the complete solenoid operation thereof in multiple channels responsive to the signal pulses that are transmitted between the distributor and printer or other primary receiving unit. The reperforator solenoids are instantaneously responsive to signal impulses transmitted to the low energy drain coil windings of the transmission banks which enable any number thereof within a practical range to be instantaneously connected to a multiple channel system.

Then, too, reperforators of the type embodying features of the present invention are simple, compact, comparatively inexpensive, and afford re-transmission of messages to a large number of

different stations without entailing any additional labor or time requirements. For instance, in selector circuits operating 250 milliamperes, series connection of one relay-plate as described ⁵ supra, will reduce the current intensity by approximately two milliamperes. Five such transmission banks connected in series between the distributor and printer would reduce the current intensity by about ten milliamperes which is ¹⁰ still trivial in that such nominal variations leave unimpaired the wide marginal surplus provided for safe operation. A reperforator embodying features of the present invention may be instantaneously connected to each transmission bank, and these are simultaneously operated to ¹⁵ record the code selections impressed upon the primary printer without impairment to the operation thereof.

One object of the present invention is to provide a reperforator that is entirely solenoid operated for multiple connection through relay units to a channel without impairing signal transmission and/or reception and/or redistribution.

Another object of the present invention is to ²⁵ simplify the construction and improve the operation of singleplex and/or multiplex circuits for effecting multiple reception, distribution or redistribution of electrically transmitted signals.

Still another object is to provide an electrically ³⁰ operated reperforator that is simple, compact, comparatively inexpensive, and capable of multiple connection to a simplex, duplex or multiplex system without impairment thereto for effecting redistribution over a plurality of signal transmitting channels.

A further object is to provide a novel reperforator device in conjunction with a transmission bank for enabling the ready incorporation of additional units thereof in any electrical transmission channel without the necessary modification of electrical circuits, resistance values or ⁴⁰ wiring changes in the original printer, distributor or reperforator circuit.

A still further object is to provide a simple, ⁴⁵ compact and self-contained reperforator unit that is capable of single or multiple inclusion in a receiving circuit of a signal transmission channel so as to afford multiple reception and redistribution without entailing any appreciable expense, time or labor.

Still a further object is to provide an inexpensive solenoid operated reperforator that is dependable and electrically responds to all variations in signal impulses when connected in single ⁵⁵ or multiple units to a transmission circuit for multiple reception and redistribution.

Other objects and advantages will appear from the following description of an illustrated embodiment of the present invention.

In the drawings:

Figure 1 is a perspective view of a skeleton reperforator arrangement embodying features of the present invention, it being shown connected to a circuit that is diagrammatically illustrated to clarify the showing.

Figure 2 is a plan view of a reperforator embodying features of the present invention.

Figure 3 is a front view in elevation of the reperforator shown in Figure 2.

Figure 4 is a sectional view taken substantially along line IV-IV of Figure 3.

Figure 5 is a sectional view taken substantially along line V-V of Figure 2.

Figure 6 is a sectional view taken substantially along line VI-VI of Figure 2.

Figure 7 is an enlarged fragmentary view of the electrical tape feed cut-out that is capable of use in conjunction with the reperforator such as illustrated in Figure 1.

Figure 8 is a schematic wiring diagram of the ⁵ electrical circuit and instrumentalities shown with more mechanical detail in Figure 1.

The structure selected for illustration comprises a bottom plate 10 which is of square or rectangular configuration and preferably though not ¹⁰ essentially of non-magnetic material such as bakelite or other insulating composition. In this instance, another plate 11 is disposed above the bottom plate 10, it being of similar size, shape and composition for spaced parallel support by ¹⁵ a plurality of studs 12 which have lock nuts 13 with spacer collars 14 disposed therebetween to rigidly maintain the bottom and base plates 10 and 11 in spaced parallelism. The spaced parallel bottom and base plates 10 and 11 serve to ²⁰ receive the wiring therebetween for connection to the instrumentalities to be hereinafter described.

A plurality of code and tape feeding solenoids are mounted in pairs, in this instance six pairs, ²⁵ 15-16, 17-18, 19-20, 21-22, 23-24, and 25-26, on triangular plates 27, 28, 29, 30, 31, and 32 disposed and supported in substantially radial relation on the top base plate 11 with their apex centrally grooved to provide a compact arrangement. These triangular plates 27 to 32 are sustained by threaded studs 33 which project through the corner regions thereof for threaded engagement therewith so that their free extremities will engage the top base plate 11 to serve ³⁰ as an adjustable support in conjunction with threaded studs 34 which are disposed intermediate each of the solenoid pairs 15-16, 17-18, 19-20, 21-22, 23-24, and 25-26 to project through and connect yoke plate 35 and the triangular plates 27 to 32 for threaded engagement ³⁵ with the top base plate 11. In consequence thereof, the triangular solenoid supporting plates 27 to 32 are secured in position for vertical adjustment as conditions may require for better ⁴⁰ and more satisfactory operation.

As shown, each of the solenoids 15 to 26 are provided with iron cores 36 which project from the upper ends for magnetic cooperation with armature bars 37 which are pivotally supported ⁴⁵ in superimposed linear alignment therewith. In the present embodiment, the armature bars 37 are substantially rectangular in configuration, and are fulcrumed about pins 38 which bridge the furcated extremity 39 of standards 40 disposed in front of each pair of coils 15-16, 17-18, 19-20, 21-22, 23-24, and 25-26, for vertical support by each of the triangular plates 27 to 32, respectively.

In order to provide a greater magnetic attraction between the solenoid cores 36 and the armature bars 37, a metallic bracket 41 (Figure 2), in this instance of substantially U-shaped configuration, envelopes the armature bars 37 for attachment thereto by means of pins or other ⁵⁰ fasteners 42 so that the bottom of the bracket 41 will be in close proximity with the solenoid cores 36 within the magnetic lines of force that emanate from the pairs of solenoids or electromagnets 15-16, 17-18, 19-20, 21-22, 23-24, and 25-26. So as to limit the initial position of the armature bars 37 a post 43 is fixed to the triangular plates 31 proximate to their outward edge in radial alignment with the solenoids ⁵⁵ 15-16, 17-18, 19-20, 21-22, 23-24, and 25-26. ⁶⁰ So as to limit the initial position of the armature bars 37 a post 43 is fixed to the triangular plates 31 proximate to their outward edge in radial alignment with the solenoids 15-16, 17-18, 19-20, 21-22, 23-24, and 25-26. ⁶⁵ So as to limit the initial position of the armature bars 37 a post 43 is fixed to the triangular plates 31 proximate to their outward edge in radial alignment with the solenoids 15-16, 17-18, 19-20, 21-22, 23-24, and 25-26. ⁷⁰ So as to limit the initial position of the armature bars 37 a post 43 is fixed to the triangular plates 31 proximate to their outward edge in radial alignment with the solenoids 15-16, 17-18, 19-20, 21-22, 23-24, and 25-26. ⁷⁵ So as to limit the initial position of the armature bars 37 a post 43 is fixed to the triangular plates 31 proximate to their outward edge in radial alignment with the solenoids 15-16, 17-18, 19-20, 21-22, 23-24, and 25-26.

25—26, so as to receive the extremities of the armature bars 37 within the slot 44 provided proximate to their upper ends for communication with an axial aperture that threadedly receives an adjusting screw 45. The adjusting screw 45 extends within the slot 44 for any desired distance so as to control the initial position of the armature bars 37 that are normally urged downwardly at their inward extremities through 10 the urge of a coil spring 46 that is attached thereto at one extremity thereof for anchored attachment at their other extremity to the apertured inward extremities 47 of the triangular plates 31. In order that the armature control screw 45 may 15 be maintained in its adjusted position, a lock nut 48 is provided thereon to engage the upper extremity of the posts 43 (Figure 3). Consequently, the spring 46 will return the armature bars 37 to their initial position when the pairs of solenoids 20 15—16, 17—18, 19—20, 21—22, 23—24, and 25—26 have been de-energized.

The solenoids 15—16, 17—18, 19—20, 21—22, 25—24, and 25—26 preferably though not essentially are wound from number thirty-five gauge 25 copper enamelled wire with sufficient turns to provide approximately 400 ohms of resistance for each pair; therefore, each singular solenoid coil will have resistance of approximately 200 ohms. The windings on these coils terminate in leads 30 49 and 50, the former being connected to terminals 51—52 fixed to a terminal supporting plate 53 which, in turn, is attached to the posts 43 by means of screw fasteners 54. The lead wire 49 projects through the top base plate 11 for confinement 35 in a conduit 55 that terminates in a plug 56 which confines a plurality of terminal receptacles 57 for attachment to a complementary socket element comprising a part of a transmission bank as will appear more fully herein- 40 after.

It is to be noted that the armature bars 37 terminate inwardly in reduced extremities 58 which project through correspondingly shaped slots provided in the extremities of punch rods 45 59, in this instance six, that are vertically guided in a chambered bracket 60 of substantially rectangular cross section having horizontally spaced bottom and top sides 61 and 62. The chambered bracket 60 is supported in this instance by a 50 standard 63 which extends downwardly to the top base plate 11 for attachment thereto by means of fasteners 64. Vertically aligned apertures are provided in the bottom and top 61 and 62 of the chambered guide member or bracket 55 60 to guide the punch rods 59 that extend upwardly for cooperation with a plate 65 that is disposed thereon to provide correspondingly aligned apertures 66 for the reception of the punch rods 59 at the end of their stroke responsive to the energization of the solenoids 15—16, 17—18, 19—20, 21—22, 23—24, and 25—26.

It is to be noted that the top member 62 of the guide bracket 60 is provided with a groove 67 fixed to correspond with the cross sectional 65 configuration of the paper tape 68, thereby allowing its passage therealong underneath the plate 65 to effect the perforation thereof responsive to the operation of the punch rods 59 that discharge the material resulting from the perforation above the plate 65 for reception in a channelled member 69 which comprises a part of the guide plate 65 serving as the bottom thereof. The channelled member 69 terminates in a 70 spout 70 which directs the waste punch material 75

to a glass or other receptacle 71 supported therebeneath by the top base plate 11.

The paper tape 68 is passed along the grooved top surface of the bracket members 62 by means of a feeding member comprising a sprocket wheel 72 fixed to a shaft 73 journaled in suitable bearings to carry a ratchet wheel 74 at the extremity thereof in confronting relation with a pawl 75. The teeth of the sprocket wheel 72 engage the feed holes or perforations 76 previously punched in the tape 68 for positive feeding thereof responsive to the pawl actuated ratchet wheel 74. To insure positive tape feeding, the tape 68 is maintained in contact with the feeding sprocket wheel 72 by means of a transversely disposed shoe 77 which comprises a vertically disposed plate 78 having spaced ears 79 for receiving a pintle 80 therebetween. The pintle 80 is mounted to an arm 81 (Figure 2) that is fixed to the extremity 82 of the feed sprocket shaft 73, thereby supporting the shoe 77 above the tape 68. The shoe 77 has an arcuate furcated extension 83 which projects longitudinally of the tape 68 along the median line thereof to exert a pressure thereon with the sprocket wheel 72 serving to sustain the tape 68 so that registry is effected between the sprocket wheel teeth and the linear feed perforations 76.

This is insured by a spring 84 which envelops the pintle 80 between the shoe ears 79 to normally urge the shoe 77 and its furcated extension 83 in a clockwise direction (viewed from Figure 4) for application of the tape 68 onto the sprocket wheel 72. A tape guide plate 85 is slotted to correspond with the cross-section of the tape 68 which passes therethrough just above a flat sustaining member 86 which supports the slotted guide plate 85 at its edge to maintain the tape 68 in linear alignment along its path of traverse over the punches 59 mounted in their bracket housing 60. The tape 68 is furnished from a roll (not shown) which may be supported in a reel fitted to any part of the frame 10—11 or above the instrumentalities described supra as commercial practice may dictate.

Now, then, the pawl 75 is, in this instance, joined to a plate 87 which is attached to an iron rod 88 comprising a core of a feeding solenoid or electro-magnet 89 mounted on a plate member 90 by an axially disposed lug 91 which serves as a 50 limit stop for the core rod 88. The solenoid supporting plate 90 is sustained upon the base plate 11 by means of threaded studs 92 which have nuts 93 in engagement therewith to properly space and support the plate 90 in its desired position relative to the ratchet wheel 74 so that the pawl 75 will be in proper relation thereto to impart intermittent rotation thereto responsive to the reception of the solenoid core 88.

As shown, the solenoid supporting plate 90 has upstanding side walls 94 and 95, the latter being provided with an angular bracket 96 attached to the top thereof so as to provide a horizontal extension 97 for carrying an adjusting stud 98 which is in threaded engagement therewith to project vertically therethrough in the path of the pawl plate 87 so as to limit its upward movement. The position of the screw 98 relative to the pawl plate 87 is maintained by the lock nut 99 in threaded engagement with the stud 98 so that the downward and upward movement of the solenoid core 88 together with its attached pawl 75 is controlled by the lug 91 and the adjustable stud 98, respectively. A spring 100 is anchored at one end thereof to a pin 101 carried by the 75

pawl plate 87 while the other extremity thereof is mounted to a stud 102 fixed to the top corner region of a vertical standard or plate 63 described supra.

5 Another spring 103 is fixed at one extremity thereof to the stud 102 for a vertically downward extension with the other extremity thereof fixed to a bell crank lever 104 pivoted about a stud 105 anchored in the vertical standard or plate 10 63 so that the other arm 106 of the bell crank lever 104 will carry a roller 107 for registry with the space between the teeth of the ratchet wheel 15 74, thereby retaining the latter to its intermittently and successively actuated position responsive to the pawl 75. It is obvious, therefore, that the ratchet wheel 74 has no freedom of movement except responsive to the positive actuation of the pawl 75 in that the rollers 107 serve as an indexing expedient under the influence of the spring 20 103 which normally maintains such an engagement with the periphery of the ratchet wheel 74.

It should be observed, however, that the feeding solenoid core rod 88 is normally maintained in its extreme upward position when the solenoid 25 89 is de-energized, this being accomplished by a spring impelled member 108 which has an extension 109 (Figures 1 and 7) that projects beneath the pawl plate 87, it being urged upwardly by means of a spring 110 to return the pawl 15 30 to its initial position after each actuation. A lead wire 111 connects the windings of the solenoid 89 to a tubular jack 57 comprising a part of the plug 56. Another lead wire 112 extends from the windings of the solenoid 89 to a pair of coils 35 113 and 114 supported by a bracket 115 fixed to a vertical plate 116, the coils 113 and 114 serving as a cut-out for the feeding solenoid 89 when employed in conjunction with a Mux system wherein the six-pulse is always beating to punch feed 40 holes in the tape 68 and to constantly effect the feeding thereof even though there is no code selection as will appear more fully hereinafter.

The vertical cut-out coil supporting plate 116 is supported by a metallic bracket 117 which is attached at the bottom thereof to the top base plate 45 11 by one of the fastener nuts 13 thereof. A bolt 118 extends through the top of the bracket 117 and the plate 116 to effect the support thereof with the feed cut-out solenoid coils 113 and 114 50 having a horizontal top bracket plate 119 attached to the cores 120 and 121 thereof by means of nut fasteners 122 and 123, respectively. The top horizontal bracket plate 119 has its edge secured to the supporting plate 116 to confront the 55 horizontal bottom plate 115 that is similarly attached, thereby supporting the feed cut-out solenoids 113 and 114 therebetween. The solenoid coils 113 and 114 are connected in series and have a total resistance of approximately forty ohms 60 so that their cores 120 and 121 will cooperate with an armature 125 (Figures 1 and 7) as will appear more fully hereinafter.

The cut-out armature 125 is, in this instance, of key-shaped configuration (Figure 2) so as to 65 present transversely aligned ears 126 and 127 with an intermediate ear 128 along the longitudinal median line of its elongated body 129. The transversely aligned ears 126 and 127 are provided with depending pins 130 for registry 70 with correspondingly sized apertures provided in a transversely disposed strip 131 fixed to the horizontal top plate 119. The strip 131 serves as a support for the armature pins 130 which is a fulcrum for the solenoid armature 125. This 75 arrangement provides a sensitive mount for the

5 armature 125 which will respond to slight electrical impulses and be capable of delicate adjustment. The armature 125 has a longitudinally disposed insulation plate 132 fixed thereon to confront an upward limit stud 133 adjustably carried by a post 134 anchored in the horizontal top plate 119.

10 A threaded stud 135 (Figure 3) is fixed to the extremity of the armature 125 to adjustably control a resilient terminal or contact 136 mounted on the underside of the armature 125 to confront a contact terminal 137 fixed to the solenoid top plate 119 for connection through a wire 138 to a tubular terminal jack 57 provided in the plug 15 56. As described supra, the plug 56 has a sufficient number of terminal jacks 57 for lead wires 49, 111, and 138 coming from each of the solenoids 15, 17, 19, 21, 23, 25, 89, and 114 for instantaneous connection to a transmission bank as will appear more fully hereinafter. A coil spring 20 139 is anchored to a nut 140 in threaded engagement with an elongated stud 141 which extends downwardly through the bottom coil plate 115 for engagement therewith. A lock nut 142 engages the spring adjusting nut 140 to preclude the accidental displacement thereof so that the tension in the spring 139 will not vary unless adjusted.

25 A rod 143 extends from the spring 139, it having the free extremity thereof provided with an enlarged head for lodgment in an aperture through a slotted lateral opening provided in the ear 128 of the armature 125. Consequently, the spring 139 normally urges the armature 125 in a counterclockwise direction (viewed from Figure 3) for a distance determined by the stud 133 so as to normally effect the separation of the terminals 136 and 137 when the solenoid coils 113 and 114 are de-energized. A spring plate or latch 144 is 30 pivoted to the armature 125 so as to engage the coiled spring extension rod 143 for attachment retention by the armature against accidental displacement and to insure a firm electrical connection to the lead wire 112 in circuit with the winding of the feed coil 89. The convolutions 35 comprising the windings around the peripheral surfaces of the cut-out cores 120 and 121 to comprise the coils 113 and 114 are connected through lead wires 145 and 146 in series with lead wires 137-138 and 50 in circuit with the tape feeding 40 coil 89 through the armature 125 and the code bar solenoids or electromagnets 15-16, 17-18, 19-20, 21-22, 23-24, 25-26, respectively. In the so-called Mux system, therefore, the tape 68 will not feed unless a code selection is first made 45 through the code bar solenoids 15-16, 17-18, 19-20, 21-22, 23-24, and 25-26. It is to be noted that the feed punch solenoids 25 and 26 have their terminal leads 49-50 connected to the 55 source of power supply through lead wires 147-148 that are, in this instance, connected to the lead wire 112 and tubular jack 57, respectively, the lead wire 148 having its own jack 57 in the plug 56 while lead wire 147 is connected to the same jack 57 in which the lead wire 111 terminates. As a 60 result, the lead wire 50-147 of the coils 25-26 is grounded by connection to the terminal and lead wire 137-138 through the armature 125 of the cut-out coil 113-114 so as to stop beating of the feed hole punch and the tape feed that is 65 actuated by the coils 25-26 and 89. This places the ground through the cut-out armature 125 rather than direct so that both the feeding as well as the beating of the feed punch is eliminated 70 when no signal code selection takes place. 75

It should be understood that the sixth pulse cut-out solenoids 113 and 114 together with its auxiliary instrumentalities described supra, are only included when the above described perforator device is connected through the plug 56 to a transmission bank 150 having a plug 151 provided with jack pins 152 complementary to the tubular jacks 57, to the so-called Mux telegraphic circuit. The Mux circuit has a constantly beating sixth pulse which would ordinarily punch feed holes 76 in the tape 68 and effect the feeding thereof even though no code selections effected through any one or all of the first five pulse circuits. This sixth pulse tape feed cut-out mechanism functions when there are no code selections, since the terminals 136-137 are normally separated unless a code selection is made previous to the operation of the sixth pulse which sends current through the solenoids 113 and 114, thereby effecting contact between terminals 136-137 to energize the feed solenoid 89 to feed the tape 68 one step forward within the capacity of the ratchet wheel 74 and pawl 75.

The residual magnetism in the solenoid cores 120-121 holds the armature 125 down for continued contact between the terminals 136-130 for at least one complete operation to insure feeding of the tape 68 for the next code selection. However, the feed punch 59 operated by solenoids 25 and 26 is first energized by the sixth pulse transmission bank relay 153 which permits its double acting armature 154 to contact with the terminal 155 during its up-stroke. This permits current to pass through the resistance 156 whose terminal cooperates with a manual switch 157 for connection to the terminal jack pin 152 that leads to the wire 148 connected to the feed punch solenoids 25-26. On the down stroke of the armature 154 responsive to the energization of the transmission relay 153, armature contact is effected with the terminal 158 that closes the circuit through the wire 159 having connection to a jack pin 152 which connects with the lead wire 138 by means of the tubular jack 57 when the complementary plug elements 56 and 151 are in telescopic engagement, this being necessary or at least highly desirable in connecting the reperforator through the transmission bank 150 that receives its impulses for feeding of the tape 68 and recording the code selections through the operation of the punches 59 from the printer 160 that is connected to the distributor 161 comprising conventional telegraphic equipment.

Now, then, in a start-stop telegraphic system, the cut-out solenoids 113 and 114 are not required, and these may be shunted from the circuit by means of switch jacks 162 mounted on the vertical plate 116 thereby affording the operation of the punch and feed solenoids 25-26 and 89, respectively, without interference or influence from the cut-out coils 113 and 114. Further, the transmission bank 150 has lead wires 162 that are in electrical connection with terminal pins 152 for placing the first five code selection armatures 163 which cooperate with relays 164 having lead wires 165 and 166 terminating in jack pins 167 and 168, respectively, for telescopic engagement with corresponding opposite plug sections 169 and 170 extending from the secondary printer and distributor as will appear more fully hereinafter. A small ammeter 171 is in circuit for rapid and precision adjustment of the armatures 154 and 163, in this instance six, of the relays 153 and 164. The ammeter terminals 172 and 173 are in circuits with the resistors

174, 175 and 176 through pin jacks 177 and 178 so that interchanging the pin jacks 177 and 178 reverses the current through the meter 171 when a negative battery is employed in connection with the power source leads 179 and 180 which are in circuit with the relay terminal contacts 181 and the jack pins 168 for furnishing power to the reperforator 10 described supra.

The ammeter 171 is shunted out when not used for adjustment purposes so that it is selectively incorporated in the relay circuits. Another pair of pin jacks 182 and 183 are provided in the relay circuits, the relays 153 and 164 being so grouped that resistance 174 is in circuit with the single sixth pulse relay armature 154 (extreme left in Figure 1) while resistances 175 and 176 serve the remaining five selector relays 164 which operate the selector solenoids or magnets on the reperforator. These resistances 174, 175 and 176 each have an approximate resistance of 100 ohms and serve to determine the current flow through the sixth pulse relay 153 and remaining five selector relays 164. Now, then, by interchanging the pin jacks 182 and 183 (Figure 1) the meter 171 will be transferred from the sixth pulse relay 153 to the bank of five selector relays 164 for adjustment of the relay armatures 163 thereon. A manual switch 184 is placed in the battery circuit to enable the disconnection of the power source from the relay contacts 158 and 181 and solenoids 15-16, 17-18, 19-20, 21-22, 23-24, and 25-26 that operate the reperforator punches 59. An exteriorly accessible cord 185 constituting an extension of the switch 184 is also provided for the purpose of disconnecting the battery from the relay contacts 158 and 181 and the power to the reperforator solenoid coils 15 to 26. The cord extension 185 is used when the transmission bank 150 is completely confined by a housing or the interior otherwise rendered inconveniently accessible.

The details of this transmission bank 150 and the manner of its operation together with the adjustment of the armatures 154 and 163 are fully disclosed in my Letters Patent 2,023,290, dated Dec. 3, 1935. This relay action is accomplished by connecting plug 151 to the reperforator 10 which is provided with a complementary plug attachment 56, and thereupon the plug containing pin jacks 168 is connected to the complementary tubular jacks provided in a plug body 170 which have lead wires connected to a standard telegraphic distributor 161. Then, too, the plug body containing the pin jacks 161 is connected with complementary tubular jacks provided in a plug body 169 which have lead wires connected to the standard primary printer 160, thereby placing the printer coils in circuit with the relay coils 153 and 164 so that the desired number of additional secondary reperforators may be placed in series through corresponding transmission banks or relay plates 150 by establishing connection with their respective plugs 151 to function simultaneously with the primary printer. This relay-plate 150 has low energy drain coils 153 and 164 which enable any practical number of corresponding units to be incorporated in the printer circuit without interruption or impairment to its operation. Consequently a corresponding number of reperforators 10 can be readily connected for automatic transmission of the same message by means of reperforated copy to any number of different stations through tape transmitters or by printer extensions to local or even remote locations.

For each additional secondary reperforator 75

that produces a tape copy, a relay-plate 150 of the type described supra may be incorporated into the distributor or primary printer circuit so long as the additional resistance thereof will not impair the operating margin of the current intensity required for the primary printer and/or reperforator and/or for the added secondary printers and/or reperforators. The feature of trivial resistance values in the relay-plate or bank 150 together with the solenoid operated reperforator 10 embodying features of the present invention, is of primary importance in that the series connection of a large number (as many as five or more) of the above described relay-banks 150 to distributor circuits have proven successful. Trivial resistance values are made possible in a large measure by the precision adjustment afforded by the test ammeter 174 and the sensitive mounting of the relay armatures 154 and 163 which enable the use of low resistance relay coils 153 and 164. It should be noted that when the switch 157 is displaced to connect with lead wire 180, the relay bank 150 functions precisely as described in my copending patent application, its special use in connection with the reperforator 10 is to operate the sixth pulse solenoid 89 which moves the tape forward. Also the seventh wire is used to operate the feed hole solenoids or magnets 25 and 26 through relay terminals contact 155 which contact 158 controls the solenoid 89; consequently relay armature 154 has a double contact 155-158 instead of only a single contact disclosed in my copending patent application.

It is worthy of note that the pulses received by the primary distributor 161 are of relatively brief duration, and these short pulses serve to set up combinations in the primary printer 160 which is designed to respond to such pulses. These pulses, however, are much too short or weak for the direct operation of any additional receiving unit whether such be the reperforator 10 or an additional printer (not shown) connected in series with the primary printer 160. These short primary pulses are lengthened by resort to the transmission bank 150 that has a precision meter 171 purposed for the adjustment of the relay armatures 154 and 163 (Figures 1 and 8) to precisely determine, adjust and extend the length of the pulses received from the primary distributor 161. The residual magnetism of the iron cores in the relay coils 153 and 164 serve to retard the break of the contacts 158 and 181 with their respective armatures 154 and 163 to provide the necessary time interval for successfully performing perforation by the direct action of the reperforator pins 59 on the tape 68 (Figure 1) effected by the magnet coils 15 to 26.

The operation of the reperforator 10 (Figures 1, 2, and 8) is as follows: As described supra, the six relay coils 15-16, 17-18, 19-20, 21-22, 23-24, and 25-26 are connected in series to the six primary printed circuits 165-166 through lead wires 49 having a common return 50-112-146-138 with their connection to the aforesaid primary printer circuits 165-166 controlled by five code armature-relay units 163-164 and one sixth pulse feeding armature-relay unit 153-154 (Figure 8). These relay coils 153 and 164 are of low or negligible resistance so that their inclusion in the primary printer circuits 165-166 will not impair the working balance thereof.

Now, then, assuming the letter "L" is represented by the combined operation of the second and fifth perforating code bars 31 of the coils 17-18 and 23-24 with the first, third, fourth pulses rep-

resented by coils 15-16, 19-20, and 21-22, respectively, remaining inoperative, and that this particular code selection is effected by the distributor 161. Then the second and fifth pulse primary circuits 165-166 (viewed from right in Figure 8) close to correspondingly operate the primary printer 160, and the second and fifth relay contacts 181 (viewed from the right—Figure 8) also close to energize coils 17-18 and 23-24 which directly actuate their respective code bars 31 and perforator pins 59 (Figure 1) operatively connected therewith.

After the second and fifth pulses or any of the five code pulses have been operated for different combinations controlled by the distributor 161, a local contact (not shown) embodied as an element of every distributor 161, closes and energizes the sixth pulse relay coil 153 which, in turn, operates the feed magnet 25-26 of the reperforator 10 to move the tape 68 one step forward (Figure 1). As the armature 154 is restored to its initial position upon the breaking of the primary sixth pulse circuit 165-166 (viewed from the right in Figures 1 and 8) a contact 158 which also serves as a back stop for the armature 154, closes the circuit 111-148 to operate the feed hole perforator magnet 89 resulting in a feed hole perforation 76 on the tape 68 (Figure 1), thereby completing one full operation with all of the instrumentalities returned to initial inoperative position for succeeding operation of any code combinations in a similar manner as effected by the primary distributor 161.

It is to be noted that the common return 138-146 (Figure 8) of the five code circuits 49-50 pass through coils 113-114 constituting the sixth pulse cut-out magnet, the armature 125 and contact 137 of said magnet 113-114 controlling the closing of the two circuit wires 49-50 and 111-112 leading to the feed magnet 25-26 and feed hole perforator magnet 89. Should no code selection be made, the sixth pulse cut-out magnet 113-114 will function to prevent the operation of the feed magnet 25-26 and feed hole perforator magnet 89. This occurs owing to the fact that the cut-out magnet armature 125 remains disengaged relative to its contact 137 for rendering the feed hole magnet 25-26 and feed magnet 89 inoperative so that blank tape 68 will not be fed until another code selection is made. The armature 125 is so adjusted as to cause contact with the terminal 137 for a complete operation owing to the residual magnetism possessed by the iron cores of the coils 113-114. In multiplex circuits as shown in Figure 8, the distributor 161 operates the sixth pulse even though no code selection is made during each operation so that the cut-out magnet 113-114 serves the important function of precluding unnecessary feed hole perforator action and useless feeding of the tape 68. In start and stop systems, the cut-out magnet 113-114 is not necessary.

Various changes may be made in the embodiment of the invention herein specifically described without departing from or sacrificing any of the advantages of the invention as defined in the appended claims.

I claim:

1. A reperforator including a plurality of pulse circuits for electrical signal recordation comprising a plurality of electromagnets, electrical means in said pulse circuits for lengthening the pulses to correspond with the electrical requirements of said electromagnets to insure their proper operation, code bars operatively connected to said elec-

tromagnets to serve as armatures thereof, means for directing a tape in the path of said code bars, and an additional electromagnet for directly feeding said tape responsive to the operation of any one or combination of said code bars.

5 2. A reperforator including a plurality of pulse circuits for electrical signal recordation comprising a plurality of electromagnets, electrical means in said pulse circuits for controlling the duration of the pulses to said electromagnets, code bars operatively connected to said electromagnets to serve as armatures thereof, means for directing a tape in the path of said code bars, and means comprising an additional electromagnet for directly feeding said tape responsive to the operation of any one or combination of said code bars.

3. A reperforator including a plurality of pulse circuits for electrical signal recordation comprising a plurality of electromagnets, armature code bars directly responsive to said electromagnets, means for directing a tape in the path of said code bars, tape perforating pins connected to said code bars, means for feeding said tape responsive to the operation of any one or combination of said code bars, an electrical circuit connected to said electromagnets for selectively distributing electrical impulses to said electromagnets to effect the energization thereof for corresponding code bar operation, and means in said electrical circuit for changing the pulses to correspond with the electrical requirements of said electromagnets to insure their proper operation.

4. A reperforator for electrical signal recordation comprising a plurality of electromagnets, code bars comprising a part of the armatures of said electromagnets, means for directing a tape in the path of said code bars, another electromagnet, said last named relay having a code bar armature, a pin connected to said last named armature, a pin connected to said last named armature, a code bar for perforating feed holes in said tape, a pawl operatively connected to said last named electromagnet, a ratchet wheel in the path of said pawl, means operatively connected to said ratchet wheel for intermittently feeding said tape during one directional stroke of said last named code bar responsive to the energization of said last named electromagnet, and means for effecting a feed hole perforation in said tape during the opposite directional stroke of said last named code bar.

5. A reperforator including a plurality of pulse circuits for electrical signal recordation comprising a plurality of electro-magnets, code bars operatively connected to said electro-magnets, means for directing a tape in the path of said code bars, another electromagnet, said last named electromagnet having a code bar armature, a pin connected to said last named armature code bar for perforating feed holes in said tape, a pawl operatively connected to said last named electromagnet, a ratchet wheel in the path of said pawl, means operatively connected to said ratchet wheel for intermittently feeding said tape responsive to the energization of said last named electro-magnet, and electrical relays connected to said electromagnets for selectively distributing and controlling the electrical impulses to said electromagnets to effect the intermittent feeding of said tape and the operation of said code bars for recording 70 the message on said tape.

6. A reperforator including a plurality of pulse circuits for electrical signal recordation comprising a frame, a plurality of code bars in predetermined alignment on said frame, means for guiding a tape in the path of said code bars, electro-

magnets grouped on said frame, said electromagnets having armatures connected to said code bars to directly effect the operation thereof, an additional electromagnet for intermittently feeding said tape prior to code bar operation to effect the 5 perforation of said tape responsive to selective signal energization of said code bar electromagnets, and means in said pulse circuits for lengthening the impulses to correspond with the electrical requirements of said electromagnets to insure their proper operation.

7. A reperforator including a plurality of pulse circuits for electrical signal recordation comprising a frame, a plurality of code bars in predetermined alignment on said frame, means for guiding a tape in the path of said code bars, electromagnets grouped on said frame, said electromagnets having armatures connected to said code bars to effect the operation thereof, means including an electromagnet for intermittently feeding said tape prior to code bar operation to effect the perforation of said tape responsive to selective signal energization of said code bar electromagnets, and means in said pulse circuits for changing the impulses to correspond with the electrical requirements of said electromagnets to insure their proper operation.

8. A reperforator including a plurality of pulse circuits for electrical signal recordation comprising a frame, a plurality of code bars in predetermined alignment on said frame, means for guiding a tape in the path of said code bars, electromagnets grouped on said frame, armatures between said electromagnets and code bars for operating said code bars, means including an electromagnet for intermittently feeding said tape prior to code bar operation to effect the perforation of said tape responsive to selective signal energization of said code bar electromagnets, means in said pulse circuits for lengthening the 30 impulses to correspond with the electrical requirements of said electromagnets to insure their proper operation, said electromagnets having lead wires extending from the coils thereon, and a plug combining said lead wires for instant connection to an electrical circuit from which the 35 electromagnet operating signals emanate.

9. A reperforator for electrical signal recordation comprising a frame, a plurality of code bars in predetermined alignment on said frame, means for guiding a tape in the path of said code bars, electromagnets grouped on said frame, armatures confronting the coils of said relays for operative connection to said code bars for directly operating said code bars, means including an electromagnet for intermittently feeding said tape prior to code bar operation to effect the perforation of said tape responsive to selective signal energization of said code bar electromagnets, said electromagnets having lead wires extending from the coils thereon, and electrical relays connected to said electromagnets for controlling and selective signal conductance thereto to energize corresponding electromagnets for the purpose set forth.

10. A reperforator for electrical signal recordation comprising a frame, a plurality of code bars in predetermined alignment on said frame, means for guiding a tape in the path of said code bars, electromagnets grouped on said frame, armatures confronting the coils of said electro-magnets for connection to said code bars for directly operating said code bars, means including an electromagnet for intermittently feeding said tape prior to code bar operation to effect the perforation of 70

said tape responsive to selective signal energization of said code bar electromagnets, said electromagnets having lead wires extending from the coils thereon, electrical relays connected to said 5 electromagnets for controlling and selective signal conductance thereto to energize corresponding electromagnets, and a separable plug connection between said transmission bank and the lead wires of said magnet coils so that ready connection and disconnection can be effected there- 10 between.

11. A reperforator for electrical signal recordation comprising a frame, a plurality of code bars in predetermined alignment on said frame, means 15 for guiding a tape in the path of said code bars, electro-magnets grouped on said frame, armatures confronting the coils of said electromagnets for connection to said code bars to effect the operation thereof, means including an electromagnet 20 for intermittently feeding said tape prior to code bar operation to effect the perforation of said tape responsive to selective signal energization of said code bar electromagnets, said electromagnets having lead wires extending from the 25 coils thereon, electrical relays connected to said electromagnets for controlling and selective signal conductance thereto to energize corresponding electromagnets, and means for precluding the feeding tape unless said signal code bar electromagnets 30 are energized responsive to a code selection for message recordation on said tape.

12. A reperforator for electrical signal recordation comprising a frame, a plurality of code bars in predetermined alignment on said frame, means 35 for guiding a tape in the path of said code bars, electromagnets grouped on said frame, said electromagnets having armatures connected to said code bars to effect the direct operation thereof responsive to each code impulse or combination of 40 impulses, means including an electromagnet for intermittently feeding said tape prior to code bar operation to effect the perforation of said tape responsive to selective signal energization of said code bar electromagnets, said electromagnets 45 having lead wires extending from the coils thereon, electrical relays connected to said electromagnets for selective signal conductance thereto to energize corresponding electromagnets, and means including a relay mechanism for precluding 50 the feeding of the tape unless said signal code bar electromagnets are energized responsive to a code selection for message recordation on said tape.

13. A reperforator for electrical signal recorda-
55 tion comprising a frame, a plurality of code bars
in predetermined alignment on said frame,
means for guiding a tape in the path of said code
bars, electromagnets grouped on said frame, said
electromagnets having armatures connected to
60 said code bars to effect the direct operation there-
of responsive to each code impulse or combina-
tion of impulses, means including an electromag-
net for intermittently feeding said tape prior to
code bar operation to effect the perforation of
65 said tape responsive to selective signal ener-
gization of said code bar electromagnets, said
electromagnets having lead wires extending from
the coils thereon, electrical relays connected to
said electromagnets for controlling and selective
70 signal conductance thereto to energize corre-
sponding electromagnets, normally spaced terminals
for controlling the energization and de-
energization of said tape feeding means, and
means for effecting contact between said termi-
75 nals responsive to effecting a code selection to

provide for tape feeding with each code selection.

14. A reperforator for electrical signal recordation comprising a frame, a plurality of code bars in predetermined alignment on said frame, means for guiding a tape in the path of said code bars, electromagnets grouped on said frame, armatures extending between said electromagnets and said code bars to effect the operation of the latter directly responsive to the former, means including an electromagnet for intermittently feeding said tape prior to code bar operation to effect the perforation of said tape responsive to selective signal energization of said code bar electromagnets, said electromagnets having lead wires extending from the coils thereon, electrical relays connected to said electromagnets for controlling and selective signal conductance thereto to energize corresponding electromagnets, normally spaced terminals for controlling the energization and de-energization of said tape feeding means, and electromagnetic means for effecting contact between said terminals responsive to effecting a code selection to provide for tape feeding with each code selection. 5 10 15 20

15. A reperforator for electrical signal recordation comprising a frame, a plurality of code bars in predetermined alignment on said frame, means for guiding a tape in the path of said code bars, electromagnets grouped on said frame, armatures extending between said electromagnets and said code bars, to effect the operation of the latter directly responsive to the former, means including an electromagnet for intermittently feeding said tape prior to code bar operation to effect the perforation of said tape responsive to selective signal energization of said code bar electromagnets, said electromagnets having lead wires extending from the coils thereon, electrical relays connected to said electromagnets for controlling and selective signal conductance thereto to energize corresponding electromagnets, normally spaced terminals for controlling the energization and de-energization of said tape feeding means, and electromagnetic means for effecting contact between said terminals responsive to effecting a code selection, to provide for tape feeding with each code selection, said last named electromagnet means being possessed of sufficient magnetism to retain said terminals in contact for one complete operation to insure feeding of the tape for successive code selections.

16. A recording system of electrical circuits comprising a plurality of pulse circuits for effecting code selections, means in said circuits for prolonging the duration of the pulses, correspondingly responsive electrical circuits including code bars for effecting code bar impressions for permanent record to enable message re-transmission, means for guiding tape in the path of said code bars, and means for perforating said tape to provide feed holes therein in one directional stroke and effecting the feeding of the tape during the return stroke of said last named means.

17. A recording system of electrical circuits comprising a plurality of pulse circuits for effecting code selections, means in said circuits for prolonging the duration of the pulses, correspondingly responsive electrical circuits including code bars for effecting code bar impressions responsive to said code selections for permanent record to enable message re-transmission, means for guiding tape in the path of said code bars, and means for perforating said tape to provide feed holes therein in one directional stroke and effect- 65 70 75

ing the feeding of the tape during the return stroke of said last named means.

18. A recording system of electrical circuits comprising a plurality of pulse circuits for effecting code selections, means in said circuits for prolonging the duration of the pulses, correspondingly responsive electrical circuits including code bars, means for intermittently feeding a tape in the path of said code bars for effecting code bar impressions therein responsive to said code selections for permanent record to enable message re-transmission, means for guiding tape in the path of said code bars, and means for perforating said tape to provide feed holes therein in one directional stroke and effecting the feeding of the tape during the return stroke of said last named means.

19. A recording system of electrical circuits comprising a plurality of pulse circuits for effecting code selections, means in said circuits for prolonging the duration of the pulses, correspondingly responsive electrical circuits including code bars, means for intermittently feeding a tape in the path of said code bars for effecting code bar impressions therein responsive to said code selections for permanent record to enable message re-transmission, said last named means having a double stroke for punching feed holes in the tape in one single stroke and advancing the tape during the return stroke thereof, and means for rendering said tape feeding means inoperative unless a code selection is first made through said pulse circuits. 5 10 15
